[57] CLAIM

The ornamental design for a jump for a toy racetrack, as shown and described.

DESCRIPTION

FIG. 1 is a side perspective view of a jump for a toy racetrack showing my new design;

FIG. 2 is a perspective view showing the side opposite thereof;

FIG. 3 is a top plan view thereof;

FIG. 4 is a side elevational view thereof; the side opposite being a mirror image;

FIG. 5 is an end elevational view thereof;

FIG. 6 is an opposite end elevational view thereof; and FIG. 7 is a bottom plan view thereof.
